(57) **CLAIM**

The ornamental design for fencing assembly, as shown.

DESCRIPTION

FIG. 1 is an enlarged front elevation view of a Wicket, having a single off-set pass-through passage, that is a part of the ornamental design for fencing assembly.

FIG. 2 is an enlarged side elevation view of the Wicket of FIG. 1, viewing from the left with reference to the viewing direction of FIG. 1.

FIG. 3 is an enlarged side elevation view of the Wicket of FIG. 1, viewing from the right with reference to the viewing direction of FIG. 1.

FIG. 4 is an enlarged top view of the Wicket of FIG. 1, showing the off-set pass-through passage in the Wicket.

FIG. 5 is an enlarged view of just the pass-through passage in the Wicket, visible in FIG. 4; and,

FIG. 6 is an elevation view of an ornamental design for fencing assembly made from four Wickets according to FIGS. 1, 2, 3, 4, and 5.
